CRISPER PAN FOR DOMESTIC
REFRIGERATORS

Theodore W. Rundell, Jenkintown, Pa., assignor
to Philco Corporation, Philadelphia, Pa., a cor-
poration of Pennsylvania

Application October 19, 1940, Serial No. 361,970

9 Claims. (Cl. 312—150)

This invention relates to new and useful im-
provements in crisper pans for domestic refrig-
erators.

The use in domestic refrigerators of crisper
pans or hydrators to preserve fresh vegetables,
fruits and the like is prevalent and well known.
In the past, these devices, in many cases, have
comprised a single pan that extends entirely
across the bottom of the food compartment, while
in other cases two or more such pans have been
employed and arranged to be positioned in either
side-by-side relation or stacked one on top of
the other as desired.

This latter arrangement is preferred because
by stacking the crisper pans one upon the other
there is provided and made available space of
substantial width and height for the storage of
food-stuffs and articles of relatively large size.
However, considerable objection has been en-
countered with such arrangements of crisper
pans for the reason that prior to the present
invention they have been generally bothersome
to handle and more or less complicated struc-
tures and fastenings have been provided within
the refrigerator food compartment for securing
and holding in place the necessary crisper pan
frame structures when positioned in their side-
by-side and superimposed relationships as afore-
said.

With the foregoing in mind the principal ob-
ject of the present invention is to provide a novel
construction and arrangement of crisper pans
and frames therefor which may be secured in
either side-by-side or stacked superimposed re-
lation without the use of special fastenings or
other structure in the food compartment of the
refrigerator.

This and other objects of the invention and
the various features and details of the construc-
tion and arrangement thereof are hereinafter
fully set forth and described and shown in the
accompanying drawing, in which:

Figure 1 is a view in perspective of a refrig-
erator showing the interior thereof with the
crisper pan frame of the members of the pres-
ent invention arranged therein in side-by-side
relation.

Figure 2 is a view in perspective of a crisper
pan frame structure embodying the present
invention.

Figure 3 is a view in perspective of a pair of
frame structures disposed one above the other
and in interlocked relation.

Figure 4 is a fragmentary view in section taken
on line 4—4, Figure 3.

Figure 5 is a view in section taken on line 5—5,
Figure 2.

Figure 6 is a fragmentary view in section taken
on line 6—6, Figure 2; and

Figure 7 is an enlarged fragmentary view in
section taken on line 7—7, Figure 1.

Referring now to the drawing, and particu-
larly to Figure 1 thereof, reference numeral 10
designates, generally, a domestic refrigerator
having a food storage compartment 11 in which
is located the usual cooling unit 12 and support-
ing shelves 13. As shown in Figure 1, supported
on the bottom or floor of the refrigerator food
compartment 11 in side-by-side relation are a
pair of frame structures 14 one of which mounts
a crisper pan 15.

According to the present invention the frame
structures 14 are identical and each comprises
a heavy wire skeleton which is open at the front
20 and has parallel side portions 16, a connecting
rear portion 17, integral front legs 18 and a rear
leg or support consisting of a U-shaped member
19 welded or otherwise secured to the said rear
portion 17.

Secured in spaced relation upon the horizontal
span 19a of the member 19 are sleeves 20 of
rubber or other suitable material and correspond-
ingly secured upon the skeleton rear portion 17
are forwardly facing upstanding curved hook
elements 21, the latter on one frame being ar-
ranged for engagement by the sleeve portions 20
of another frame when two such frames are
arranged in superimposed relation as hereinafter
set forth.

Superimposed upon the side portions 16 of the
wire skeleton is a frame member 22 comprising
integral front and side portions having, respec-
tively, the cross-section shapes shown in Figures
6 and 7 of the drawing, and this frame member
40 22 has its depending side flange portions 23
welded or otherwise permanently secured to the
outer surfaces of the side portions 16 of the wire
skeleton so that the projecting flanges 24 at op-
posite upper side edges of a crisper pan 15 may
45 slidably engage over the said skeleton side por-
tions 16 (see Figure 7) thereby permitting a
crisper pan to be slidably suspended within the
said wire skeleton.

As will be observed in the drawing, the inner
50 edges of the two side portions of the frame mem-
bers 22 are formed to provide downwardly offset
inwardly projecting horizontal flanges 25 and
these flanges 25 support a member 26 of glass
or other suitable sheet material which functions
55 as a cover for the underlying crisper pan.

For the purpose of securing the frame structures 14 within the refrigerator food storage compartment 11 when resting on the bottom or floor thereof, there is provided on each of the skeleton side portions 16 a depending rearwardly facing hook element 27 and a depending finger or the like 28 arranged for cooperative engagement, respectively, with pairs of studs 29 secured to the opposite side walls of said food storage compartment 11.

These studs 29 may be ordinary shelf-supporting studs each having inner and outer radial flange portions 30 and 31 which provide therebetween a central circumferential portion 32 of reduced diameter, and they are positioned in horizontally spaced relation with the compartment 11 so that the hook element 27 on the wall side of the frame structure 14 will engage the innermost stud 29 forwardly thereof (see Figure 7) while the finger 28 engages the forward stud 29 rearwardly thereof. The hook 27 and finger 28 engage the studs 29 in the reduced central portions 32 thereof and it will be seen that when thus engaged the frame structure is secured against horizontal movement within the food compartment 11. Too, it will be observed that this construction and arrangement of hook elements 27, fingers 28 and studs 29 is such that the frame structure is prevented from tilting when the crisper pan 15 is drawn forwardly out of said frame structure. Since the frame structures 14 are of identical construction on opposite sides thereof it will be obvious that two such structures may be interchangeably secured and held in the foregoing manner in side by side relation on the floor or bottom of the refrigerator compartment 11 as shown in Figure 1.

When it becomes necessary or it is desired to remove either or both of the frame structures 14 and their pans 15 from the compartment 11, it is only necessary to tilt the forward end of the structure upwardly to clear the finger 28 from the rear of the forward stud 29 and then slide said structure forwardly to release the hooked finger 27 from the inner stud 29 after which the structure may be bodily removed from the food compartment 11. Insertion and securing of the structures into the refrigerator compartment is easily done by merely reversing the procedure employed to remove them.

As stated, the crisper pan assemblies may be disposed and secured within the food compartment 11 either in side by side relation as previously described, or they may be superimposed one upon the other in stacked relation. This latter may be done merely by placing one of the assemblies upon the other and then slightly tilting upwardly and partially withdrawing the cover 26 member of the lower assembly whereupon the upper assembly may be moved rearwardly to engage its sleeve elements 20 with the hook elements 21 at the rear of the lower, after which the said cover member 26 of the latter is lowered into place on its frame member 22 thereby holding the sleeve portions 20 in engagement with said hooks 21 and securing the two pan assemblies with respect to each other in stacked relation (see Figures 4 and 3). The upper pan assembly may be removed by first tilting and partially withdrawing the lower cover member 26 as aforesaid and then moving said upper assembly forwardly a distance sufficient to disengage its sleeves 20 from the hooks 21 at the rear of the lower assembly.

From the foregoing it will be seen that the 75

present invention provides a relatively simple and inexpensive construction and arrangement of crisper pans and frames therefor that is quite novel and enables them readily and easily to be secured in either side by side or stacked superimposed relation within a refrigerator interchangeably and without the use of special or complicated fastenings or other structures in the food compartment thereof.

10 While a particular embodiment of this invention has been herein illustrated and described, it is not intended that the invention be limited to such disclosure but that changes and modifications may be embodied and incorporated therein within the scope of the annexed claims.

I claim:

1. In a refrigerator having a food storage compartment and a pair of horizontally spaced studs secured to each side of the food storage compartment, a pair of similar frame structures arranged in said food storage compartment in relatively superimposed stacked relation on the floor of the food storage compartment and adapted to be placed in side by side relation on the floor of said compartment interchangeably, a crisper pan slidably supported by each of said frame structures and arranged for horizontal sliding movement in the compartment, means including a removable cover on each of the frame structures arranged for cooperative interengagement to secure said frame structures relative to each other in superimposed relation, and means on each of the frame structures arranged to releasably engage the studs on the adjacent side of the food storage compartment and secure the frame structures against movement when disposed on the floor of said compartment.

2. In a refrigerator having a food storage compartment and a pair of horizontally spaced studs secured to each side of the food storage compartment, a pair of similar frame structures arranged in said food storage compartment in relatively superimposed stacked relation on the floor of the food storage compartment and adapted to be placed in side by side relation on the floor of said compartment interchangeably, a crisper pan slidably supported by each of said frame structures and arranged for horizontal sliding movement in the compartment, means including a removable cover on each of the frame structures arranged for cooperative interengagement to secure said frame structures relative to each other in superimposed relation, and means on each of the frame structures arranged to releasably engage the studs on the adjacent side of the food storage compartment and secure the frame structures against movement when disposed on the floor of said compartment.

3. In a refrigerator having a food storage compartment and a pair of horizontally spaced studs secured to each side of the food storage compartment, a pair of similar frame structures arranged in said food storage compartment in relatively superimposed stacked relation on the floor of the food storage compartment and adapted to be placed in side by side relation on the floor of said compartment interchangeably, a crisper pan slidably supported by each of said frame structures and arranged for horizontal sliding movement in the compartment, means including a removable cover on each of the frame structures arranged for cooperative interengagement to secure said frame structures relative to each other in superimposed relation, and means on each of the frame structures arranged to releasably engage the studs on the adjacent side of the food storage compartment and secure the frame structures against movement when disposed on the floor of said compartment.

4. In a refrigerator having a food storage compartment and a pair of horizontally spaced studs secured to each side of the food storage compartment, a pair of similar frame structures arranged in said food storage compartment in relatively superimposed stacked relation on the floor of the food storage compartment and adapted to be placed in side by side relation on the floor of said compartment interchangeably, a crisper pan slidably supported by each of said frame structures and arranged for horizontal sliding movement in the compartment, means including a removable cover on each of the frame structures arranged for cooperative interengagement to secure said frame structures relative to each other in superimposed relation, and means on each of the frame structures arranged to releasably engage the studs on the adjacent side of the food storage compartment and secure the frame structures against movement when disposed on the floor of said compartment.

5. In a refrigerator having a food storage compartment and a pair of horizontally spaced studs secured to each side of the food storage compartment, a pair of similar frame structures arranged in said food storage compartment in relatively superimposed stacked relation on the floor of the food storage compartment and adapted to be placed in side by side relation on the floor of said compartment interchangeably, a crisper pan slidably supported by each of said frame structures and arranged for horizontal sliding movement in the compartment, means including a removable cover on each of the frame structures arranged for cooperative interengagement to secure said frame structures relative to each other in superimposed relation, and means on each of the frame structures arranged to releasably engage the studs on the adjacent side of the food storage compartment and secure the frame structures against movement when disposed on the floor of said compartment.

6. In a refrigerator having a food storage compartment and a pair of horizontally spaced studs secured to each side of the food storage compartment, a pair of similar frame structures arranged in said food storage compartment in relatively superimposed stacked relation on the floor of the food storage compartment and adapted to be placed in side by side relation on the floor of said compartment interchangeably, a crisper pan slidably supported by each of said frame structures and arranged for horizontal sliding movement in the compartment, means including a removable cover on each of the frame structures arranged for cooperative interengagement to secure said frame structures relative to each other in superimposed relation, and means on each of the frame structures arranged to releasably engage the studs on the adjacent side of the food storage compartment and secure the frame structures against movement when disposed on the floor of said compartment.

7. A refrigerator crisper pan assembly comprising a frame structure including a skeleton open at the front end and having spaced parallel side portions, a rear portion and depending supporting legs at the front and rear thereof, a frame member including front and side portions superimposed on said skeleton and permanently secured to the side portions of said skeleton, said frame member providing a surface for engagement by the depending front legs of the other frame structure when superimposed thereon, a removable cover member on each frame structure, and means secured to the rear portion of the skeleton constructed and arranged for cooperation with its removable cover member to engage a depending supporting leg at the rear of a superimposed frame structure to secure said frame structures with respect to each other in superimposed stacked relation.

8. A refrigerator crisper pan assembly comprising a frame structure including a skeleton open at the front end and having spaced parallel side portions, a rear portion and depending supporting legs at the front and rear thereof, a frame member including front and side portions superimposed on said skeleton and permanently secured to the side portions of said skeleton, said frame member providing a surface for engagement by the depending front legs of another frame structure of like construction when super-

imposed thereon, a removable cover member supported by the frame member means secured to the rear portion of the skeleton constructed and arranged for cooperation with the removable cover member to engage a depending supporting leg at the rear of a superimposed frame structure to secure said frame structures with respect to each other in superimposed stacked relation, a crisper pan having flanges along its upper side edges slidably supported in said frame structure, the flanges of said pan being engaged over the side portions of the skeleton and slidable thereon.

4. A refrigerator crisper pan frame structure including a skeleton open at the front end and having spaced parallel side portions, a rear portion, depending front legs and a depending horizontal support at the rear thereof, a frame member including front and side portions superimposed on said skeleton and permanently secured to the side portions of said skeleton, said frame member providing a surface for engagement by the depending front legs of another frame structure of like construction when superimposed thereon, a removable cover member supported by the frame member, and forwardly facing upstanding curved hook elements secured to the rear portion of the skeleton constructed and arranged for cooperation with the removable cover member to engage the depending rear horizontal support of the superimposed frame structure to secure said structures with respect to each other in superimposed stacked relation.

5. A refrigerator crisper pan assembly including a skeleton open at the front end and having spaced parallel side portions, a rear portion, depending front legs and a depending horizontal support at the rear thereof, sleeve elements on the depending rear horizontal support, a frame member including front and side portions superimposed on said skeleton and permanently secured to the side portions of said skeleton, said frame member providing a surface for engagement by the depending front legs of another frame structure of like construction when superimposed thereon, a removable cover member supported by the frame member, upstanding curved elements secured to the rear portion of the skeleton constructed and arranged for cooperation with the removable cover member to engage the sleeve elements on the depending rear horizontal support of the superimposed frame structure thereby to secure said structures with respect to each other in superimposed stacked relation, a crisper pan having flanges along its upper side edges slidably supported in said frame structure, the flanges of said pan being engaged over the side portions of the skeleton and slidable thereon.

6. A refrigerator crisper pan assembly comprising a frame structure including a skeleton open at the front end and having spaced parallel side portions, a rear portion and depending supporting legs at the front and rear thereof, a frame member including front and side portions superimposed on said skeleton and permanently secured to the side portions of said skeleton, said frame member providing a surface for engagement by the depending front legs of another frame structure of like construction when superimposed thereon, a removable cover member supported by the frame member, means secured to the rear portion of the skeleton constructed and arranged for cooperation with the removable cover member to engage the depending supporting leg at the rear of a superimposed frame structure thereby to secure said

frame structures with respect to each other in superimposed stacked relation, a crisper pan having flanges along its upper side edges slidably supported in said frame structure, the flanges of said pan being engaged over the side portions of the skeleton and slidable thereon, and a hook and finger secured in spaced relation with respect to each other on one of the side portions of the skeleton and arranged for engagement respectively with fastenings in the refrigerator interior to secure the frame structure therein against horizontal displacement.

7. A refrigerator crisper pan frame structure including a skeleton open at the front end and having spaced parallel side portions, a rear portion, depending front legs and a depending horizontal support at the rear thereof, a frame member including front and side portions superimposed on said skeleton and permanently secured to the side portions of said skeleton, said frame member providing a surface for engagement by the depending front legs of another frame structure of like construction when superimposed thereon, a removable cover member supported by the frame member, forwardly facing upstanding curved hook elements secured to the rear portion of the skeleton constructed and arranged for cooperation with the removable cover member to engage the depending rear horizontal support of the superimposed frame structure thereby to secure said structures with respect to each other in superimposed stacked relation, and elements on each side portion of the skeleton arranged for engagement with fastenings at one side of the refrigerator interior to secure the frame structure therein against horizontal and tilting movement.

8. A refrigerator crisper pan assembly including a skeleton open at the front end and having spaced parallel side portions, a rear portion, depending front legs and a depending horizontal support at the rear thereof, sleeve elements on the depending rear horizontal support, a frame member including front and side portions superimposed on said skeleton and permanently secured to the side portions of said skeleton, said frame member providing a surface for engagement by the depending front legs of another frame structure of like construction when superimposed thereon, a removable cover member supported by the frame member, upstanding curved elements secured to the rear portion of the skeleton constructed and arranged for cooperation with the removable cover member to engage the sleeve elements on the depending rear horizontal support of the superimposed frame structure thereby to secure said structures with respect to each other in superimposed stacked relation, a crisper pan having flanges along its upper side edges slidably supported in said frame structure, the flanges of said pan being engaged over the side portions of the skeleton and slidable thereon, and elements on each side portion of the skeleton arranged for engagement with fastenings at one side of the refrigerator interior to secure the frame structure therein against horizontal and tilting movement.

9. In a refrigerator having a food storage compartment and a pair of horizontally spaced studs secured to each side of the food storage compartment, a pair of similar frame structures arranged in said food storage compartment in relatively superimposed stacked relation on the floor of said food storage compartment and adapted to be placed in side by side relation on the floor of

said compartment interchangeably, said structures each comprising a skeleton open at the front end and having spaced parallel side portions, a rear portion and depending supporting legs at the front and rear thereof, a plane shelf member carried by said skeleton, forwardly facing upstanding hook means secured to the rear portion of said skeleton constructed and arranged

for engagement by a depending supporting leg of the other skeleton superimposed thereon, said shelf member normally underlying said last mentioned supporting leg to maintain said leg in interlocking engagement with said hook means to secure the skeleton structures in stacked relation.

THEODORE W. RUNDELL
